CHRISTIAN F. HEINKEL, OF CLEVELAND, OHIO, ASSIGNOR TO THE CLEVELAND TRACTOR COMPANY, OF EUCLID, OHIO, A CORPORATION OF OHIO.

TRACK BELT FOR TRACK-LAYING TRACTORS.

Application filed July 23, 1920. Serial No. 398,456.

To all whom it may concern:

Be it known that I, CHRISTIAN F. HEINKEL, a citizen of the United States, residing at Cleveland, in the county of Cuyahoga and State of Ohio, have invented a certain new and useful Improvement in Track Belts for Track-Laying Tractors, of which the following is a full, clear, and exact description.

The object of this invention is to provide a serviceable, inexpensive track belt for track laying tractors made up of units or links which are formed of pressed metal parts.

The invention consists in the construction and combination of parts shown in the drawings and hereinafter described and pointed out definitely in the appended claims.

In the drawing, Fig. 1 is a plan view of a portion of a track belt which embodies the invention in its preferred form; Fig. 2 is a vertical section of the part shown in Fig. 1; Fig. 3 is a vertical section of one of the link sides in the plane of line 3—3 on Fig. 6; Figs. 4 and 5 are vertical transverse sectional views on lines 4—4 and 5—5 of Fig. 8, through two of said link sides when their construction is slightly modified as compared to that shown in Fig. 3; Fig. 6 is a plan view of one of said link sides; Fig. 7 is a side elevation thereof looking into the open side of said link, and Fig. 8 is a plan view of a portion of a track belt of slightly modified construction. Fig. 9 is a plan view of a part of a track belt of modified construction. Fig. 10 is a sectional side elevation of the parts shown in Fig. 9 on line 10—10 of said Fig. 9; Fig. 11 is a longitudinal vertical section in the plane of line 11—11 on Fig. 9; Fig. 12 is a vertical transverse section through one link side; Fig. 13 is a sectional plan view of one of said link sides; Fig. 14 is a side elevation looking into the open side of a link side, and Fig. 15 is a sectional end view in the plane of line 15—15 on Fig. 9.

Each link is made up of three pieces, viz: a bottom plate or shoe 10, and two similar link sides 20. Each of these link sides is a sheet metal stamping,—the body 20^a of which has long, flat, parallel top and bottom edges, and substantially half-round ends,—there being an integral flange around the margin of said body and at right angles

thereto, said flange comprising a bottom portion 20^b for engagement with the shoe, a top portion 20^c which serves as a rail or track for track wheels mounted on the tractor, and two end loops 20^d, 20^e. A portion of the inner surfaces of these end loops are cylindrical, and are co-axial with and on the same radius as round holes 20^f which are punched in body 20^a near its ends.

To produce each link of the track belt, two of the described link sides are arranged in parallel relation on a shoe 10 extending longitudinally thereof. But on alternate links A and B these link sides are differently arranged with respect to each other and to the longitudinal central line of the shoe. 70

On links B the rail sides are arranged close together on opposite sides of the longitudinal central line of the shoe; while on links A the link sides are placed farther apart so that the link sides on the two contiguous links B may go between and overlap the link sides of the link A. 75

When the contiguous links are arranged as stated, the holes 20^f in the overlapping ends of the link sides should be in axial alignment. When they are, the inner surfaces of the overlapping loops 20^d and 20^e, will contribute to the formation of an eye for the reception of the pivot pin 30,— which will go through the said holes 20^f 85 and will be engaged by said loops.

The drawing shows several specific ways in which the link sides and shoe may be constructed and combined to produce track belt units or links. 90

These link sides may be secured to the shoe by bolts 25 or other suitable means, as shown in Figs. 1 and 2; or these parts may be connected as shown in Figs. 9 to 15, inclusive, by other means as will be 95 presently described.

The link sides may be so placed that the flanges on all of them will extend toward the longitudinal central line of the shoe, as shown in Fig. 9. Or these flanges on the link A may be extended toward the center line of the shoe while those on the links B may be extended toward the edges of the shoe, as shown in Fig. 1. 100

When the flanges are extended in opposite directions, they may be made to interlock, as shown in Figs. 1 to 8. In order that this may be done, notches 20^g may be

formed in the flanges of the links adjacent the ends thereof to receive the unnotched parts of the flanges of the contiguous links.

On the B links, for example, these notches may be located at each end of the link side, at about the places where the ends of the top flange 20^c join the end loops, as shown in Figs. 2 and 7. On the A links the notches may be placed at about the juncture of the ends of the bottom portion of the flange 20^b with the end loops. These notches 20^c should extend from the edges of the flanges back to the body portion 20^c. When the two links whose link sides have their flanges notched as described are assembled the flanges on each link side will go into the notches of the other link side. The width of these notches must be great enough to allow the links to turn on the pivot pins 30 relative to each other.

When the flanges are made to interlock as shown the described top flanges of the sides of the connected links form an almost continuous rail for the track wheels. This is an advantage principally because it permits the use of narrower track wheels. It is desirable to provide guides for the said track wheels, especially when the flanges of the links interlock as described. Such guides may be provided by turning up the edges of the flanges on the A-links to form the upturned guide flanges 20^h, and by punching out longitudinal tongues from the top flanges of the B links and turning said tongues upward to form the flanges 20ⁱ, which are longitudinally aligned with the flanges 20^h,—all as shown in Figs. 4, 5 and 8.

40 The construction shown in Figs. 1 to 8 is thought to be best, although, because the described notches weaken the flanges, it is necessary to use somewhat heavier metal in making the link sides.

45 In the construction shown in Figs. 9 to 15, inclusive, the shoe at one end is formed with longitudinally extended tongues 23 which are bent upward and then downward to form a loop, the end of each tongue 50 or loop being made to engage with the top of the shoe and being secured thereby by welding or other suitable means. These loops are of such internal shape and dimensions that they rotatably embrace the

55 pivot pin 30. The end of the shoe which carries the loops is therefore suspended in proper relation to the link sides from the same pivot pin which connects said link sides. The parts of the shoe between these 60 tongues is bent downward and then upward to form a ground engaging grouser 24 which is so constructed and placed that the adjacent end of the next shoe will overhang the end of the grouser, and be supported thereby. It is, of course, possible to

secure the link sides by welding or otherwise to the shoes, even when the shoes are provided with the described loops 23; and in some cases it may be desirable to do that.

70 The advantage of the construction herein described grows out of the fact that the link sides employed on all of the links are alike, and are relatively inexpensive. The difference between the links is produced 75 by the different ways of arranging these similar link sides upon the associated shoes.

Having described my invention, I claim:—

1. A track belt unit consisting of a shoe, and two similar pressed metal link sides, each comprising an elongated cup having an end portion with a substantially continuous marginal flange having flat parallel 80 top and bottom portions and approximately semi-cylindrical end loops, and means for securing said link sides in parallel relation upon said shoe.

2. A track belt unit consisting of a shoe, and two similar pressed metal link sides, each comprising an elongated cup having an end portion with an integral marginal flange having flat parallel top and bottom portions and approximately semi-cylindrical end loops, each body portion having adjacent each end a round hole which is axially aligned with and has the same radius as the inner surface of the adjacent end loop.

3. A track belt comprising a plurality of pivoted together units, each consisting of a shoe, and two similar pressed metal link sides,—each comprising an elongated cup having an end portion with an integral 100 marginal flange having flat parallel top and bottom portions and approximately semi-cylindrical end loops, the body portion having, adjacent each end, a round hole which is axially aligned with and has the same

105 radius as the inner surface of adjacent end loops,—the link sides on every other link being inserted between the link sides of the intermediate links, so that the end loops of adjacent links overlap, and pivot pins for connecting said links, each pivot pin passing through the aligned holes of the overlapping parts of the link sides and through the eye formed by the overlapping end loops of the two link sides.

4. A track belt comprising a plurality of pivoted together units, each consisting of a shoe, and two similar pressed metal link sides,—each comprising a body portion and an integral marginal flange having flat parallel top and bottom portions, and approximately semi-cylindrical end loops, said flange having notches located adjacent the ends of the link sides and extending back to the body portion, and said body portion having adjacent each end a round hole which

is axially aligned with and has the same radius as the inner surfaces of the links and loops, said link sides being differently arranged with respect to each other on the 5 shoe of alternate links as follows:—those on one set of links have their flanges turned toward the sides of the links and those on the adjacent links have their flanges turned toward the center line of the links but being 10 farther apart than those on the links first named, the link sides of adjacent links being overlapped and with the flanges on the link sides of one link arranged to project into the notches on the link sides of adjacent links, and pivot pins each of which passes through the aligned holes of the overlapping link sides and through the eye 15 formed by the overlapping end loops.

5. A track belt for tracklaying tractors 20 composed of a plurality of units pivotally connected by pins, each of said units comprising link sides and a pressed metal shoe having one end looped and embracing one of said pins, and a depending rib directly 25 under said pin.

6. A track belt for tracklaying tractors 30 composed of a plurality of pivotally connected units, each of said units comprising link sides held in alignment by a pivot pin and a pressed metal shoe having one end looped to embrace said pin and being suspended thereby and having a depending rib directly under said pin.

7. A track belt for track laying tractor 35 composed of a plurality of pivotally connected units; each of said units comprising link sides held in alignment by a pin, and a pressed metal shoe having one end thereof looped to embrace said pin and being suspended thereby, said shoe bearing against 40 said link sides and having a depending rib.

8. A track belt unit consisting of a shoe, 45 and two similar pressed metal link sides each comprising an elongated cup having an end portion with a substantially continuous marginal flange having flat parallel top and bottom portions and approximately semicylindrical end loops, each of said link sides being formed to be changed top for bottom upon said shoe, and means for securing 50 said link sides in parallel relation upon said shoe.

9. A track belt unit consisting of a shoe, 55 and two similar pressed metal link sides each comprising an elongated cup having an end portion with a substantially continuous marginal flange having flat parallel top and bottom portions and approximately semi-cylindrical end loops, each of said link sides being formed to be changed end for end 60 upon said shoe, and means for securing said link sides in parallel relation upon said shoe.

In testimony whereof, I hereunto affix my signature.

CHRISTIAN F. HEINKEL.
